(57) **CLAIM**

The ornamental design for a pet feeder as shown and described.

DESCRIPTION

FIG. 1 is a front, right and top perspective view of a first embodiment of a pet feeder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is another front, right and top perspective view of the pet feeder of FIG. 1 in a first usage state.

FIG. 12 is another front, right and top perspective view of the pet feeder of FIG. 1 in a second usage state.

FIG. 13 is another front, right and top perspective view of the pet feeder of FIG. 1 in a third usage state.

FIG. 14 is a rear, left, and bottom perspective view of the pet feeder of FIG. 13.

FIG. 15 is a front, right and top perspective view of a second embodiment of the pet feeder.

FIG. 16 is a rear, left and bottom perspective view of FIG. 15.

FIG. 17 is a front elevation view of FIG. 15.

FIG. 18 is a rear elevation view of FIG. 15.

FIG. 19 is a left side elevation view of FIG. 15.

FIG. 20 is a right side elevation view of FIG. 15.

FIG. 21 is a top plan view of FIG. 15.

(Continued)

FIG. 22 is a bottom plan view of FIG. 15.

FIG. 23 is an enlarged view of detail 24 in FIG. 15.

FIG. 24 is an enlarged view of detail 25 in FIG. 16.

FIG. 25 is another front, right and top perspective view of the pet feeder of FIG. 15 in a first usage state.

FIG. 26 is another front, right and top perspective view of the pet feeder of FIG. 15 in a second usage state.

FIG. 27 is another front, right and top perspective view of the pet feeder of FIG. 15 in a third usage state; and, FIG. 28 is a rear, left, and bottom perspective view of the pet feeder of FIG. 27.

The dashed broken lines depict portions of the pet feeder that form no part of the claimed design. The dot-dash broken lines in FIGS. 1, 2, 9, 10, 15, 16, 23, and 24 depict the boundaries of the enlargements and form no part of the claimed design.

1 Claim, 28 Drawing Sheets
